UNITED STATES PATENT OFFICE.

LOUIS MEYERS, OF NEW YORK, N. Y.

WARDROBE-TRUNK RACK.

1,405,311.

Specification of Letters Patent. Patented Jan. 31, 1922.

Application filed January 29, 1921. Serial No. 440,970.

To all whom it may concern:

Be it known that I, LOUIS MEYERS, a citizen of the United States, and resident of the city of New York, in the county of 5 Kings and State of New York, have invented a certain new and useful Wardrobe-Trunk Rack, of which the following is a specification.

This invention relates to trunks, and especially to the type commonly known as 10 wardrobe trunks, wherein a pair of hinged compartments is provided, which compartments stand on end and one of the compartments is provided with devices for suspending 15 clothes therein in a manner that prevents their being creased while contained in the trunk.

The principal object of my invention is to provide a wardrobe trunk having simplified, inexpensive, conveniently and economically 20 manufacturable, conveniently utilizable, and improved means for inserting and suspending the clothes therein and removing the same therefrom.

25 Another object is to provide means for the aforesaid purpose, wherewith, when the trunk is in open state and the clothes are undergoing insertion thereinto or removal therefrom, they will not tend to overturn 30 the trunk.

Other objects and advantages will herein-after appear.

In the accompanying drawings,—

Fig. 1 is a front elevation of the improvements constituting the invention, with the trunk sections shown as broken away, for convenience of illustration.

Fig. 2 is a plan view of the clothes supporting devices, etc., shown in Fig. 1.

40 Figs. 3, 4, and 5 show details of the invention.

The section or compartment 1 constituting the cover of the trunk is joined to the body-section 2 thereof by means of the usual 45 hinges 3. On the interior side 4 of the upper part 5 of the trunk-section 1 is located a fitting 6 that is secured to the side 4 at the corner 7, thereof, which is the intersection of its rear wall 8 and its sidewall 9 that is secured to the hinges 3. Said fitting 50 is provided with a pair of projections 10, and it is secured in place by means of a pair of wings 11 that are riveted to the walls 8, 9. To the projections 10 of the fitting 6 is piv-

oted a bracket 12 comprising a vertical 55 pivot-end 13, a horizontal or bracket portion proper, and a U-shaped end 14, both of said ends having terminals 15, 16 of reduced diameter. The bracket 12 is pivoted to the fitting 6, by the vertical portion 13 thereof 60 passing through an opening 17 in the upper projection 10 and its terminal 15 passing through a smaller opening in the lower projection 10, with its shoulder 18 bearing against said lower projection. Upon the 65 vertical extremity 19 of the U-end 14 of the bracket 12 is pivotally mounted a cross-bar 20 which is adapted to support a plurality of clothes hangers 21. Said cross-bar comprises a long horizontal portion 22 having 70 its ends 23 bent rightangularly thereto and its terminals 24 bent around parallelly thereto and facing each other, which terminals are preferably provided with knobs 25 for better appearance. To the bar-portion 22 and 75 midway between its ends 23 is secured a plate 26, by means of its end 27 being curled around the bar and riveted thereto. The plate 26 is provided with a projection 28 having an opening 29, and a smaller 80 opening 30 concentric with the opening 29, is provided in the bar-portion 22 and the curled plate-end 27, whereby the cross-bar 21 may be slipped over the bracket 12 by the opening 29 passing over the vertical ex- 85 tremity 19 of the latter and the opening 30 passing over its terminal 16, with the curled end 27 of plate 26 resting upon the shoulder 31 of the bracket, in which manner the cross-bar 20 is thus pivotally mounted upon the 90 bracket 12. A pin 32 projecting from the vertical portion 13 of bracket 12 abuts against a pin 33 extending from the upper projection 10 of fitting 6, and thereby prevents the bracket from striking the rear 95 wall 8 of the compartment, and the pin 32 abuts against a pin 34 extending from the same projection and thereby prevents the bracket from striking against the wall 9. A pin 35 extending from projection 28 of plate 100 26 abuts against a pin 36 secured to the upright extremity of the bracket 12, and thereby prevents the cross-bar 20 from turning in a clockwise direction, as viewed in Fig. 2, beyond the full line position indicated in 105 this figure. In a similar manner a pin 37 secured to the projection 28 abuts against the pin 36 and prevents the cross-bar 20

from turning counter-clockwise in an opposite direction beyond the position indicated by the dash and dot lines in Fig. 2.

When it is desired to use this wardrobe 5 trunk, the clothes may be draped over the hangers 21, and the latter may be then suspended upon the bar-ends 23, in the ordinary manner in which this type of two-point hanger is used. The cross-bar 20 with its 10 hangers and clothes may be then placed away within the compartment 1, with the said bar and bracket 12 disposed as shown in Fig. 2. Should it be desired to remove any of the clothes from the trunk, the same 15 may be very conveniently performed by merely withdrawing the cross-bar 20 away from the wall 8, and, while the bracket 12 turns about its pivot, turning the said cross-bar partially about its own pivot so as to 20 dispose the cross-bar with its hangers and clothes to about the position shown by the dash and dot lines and Fig. 2, in which position access may be very conveniently had to the clothes and for the manipulation of 25 the hangers. When the cross-bar 20 is in this position the stops 36, 37 prevent its turning in a counter clockwise direction so as to render the manipulation of the hangers more convenient, and while the cross-bar is 30 being returned with its hangers and clothes into the compartment the pins 35, 36 operate

to prevent the hangers and clothes from striking against the bracket 12.

It will be evident that the bracket 12 is supported at such a point near and relative 35 to the center of gravity of the trunk that when the device together with the hangers and the clothes is drawn out in extended operative position it is firmly supported and does not tend to overturn the trunk, and that 40 the device is otherwise simple, efficient, and convenient of manipulation.

Variations may be resorted to within the scope of the invention.

Having thus described my invention, I 45 claim:

In a wardrobe trunk a pair of hinged compartments, a bracket pivoted on the interior side of one of said compartments at a point which is adjacent its rear wall and adjacent to the wall which is hinged to said other compartment, a cross-bar pivoted between its ends to said bracket having means for supporting clothes hangers, means to limit the movement of said bracket toward 50 said two walls, and means to limit the movement of said cross-bar in opposite directions beyond a fraction of a complete revolution.

Signed at the city of New York, in the county of New York, and State of New 60° York, this 27th day of January, A. D. 1921.

LOUIS MEYERS
